UNITED STATES PATENT OFFICE.

NORMAN M. MIMS, OF SEVILLE, FLORIDA.

CLOTHES-PIN-MAKING MACHINE.

1,305,921.

Specification of Letters Patent. Patented June 3, 1919.

Application filed May 29, 1917. Serial No. 171,779.

To all whom it may concern:

Be it known that I, NORMAN M. MIMS, a citizen of the United States, residing at Seville, in the county of Volusia and State of Florida, have invented certain new and useful Improvements in Clothes-Pin-Making Machines; and I do hereby declare the following to be a full, clear, and exact description of the invention, such as will enable others skilled in the art to which it appertains to make and use the same.

The invention relates to a clothes pin making machine.

The object of the present invention is to provide a simple, practical and efficient machine of strong, durable and inexpensive construction adapted to be easily operated by one person and capable of successively operating on wire and of enabling the same to be rapidly bent and coiled to form a wire clothes pin and a ring or loop for enabling the clothes pin to be slidably placed on a clothes line of wire, or other material.

With these and other objects in view, the invention consists in the construction and novel combination of parts hereinafter fully described, illustrated in the accompanying drawings and pointed out in the claim here-to appended; it being understood that various changes in the form, proportion, size and minor details of construction, within the scope of the claim, may be resorted to without departing from the spirit or sacrificing any of the advantages of the invention.

In the drawings:

Figure 1 is an end elevation of the clothes pin making machine constructed in accordance with this invention.

Fig. 2 is a side elevation of the same.

Fig. 3 is a plan view of the clothes pin making machine.

Fig. 4 is a detail perspective view of a portion of one of the shafts or spindles.

Fig. 5 is a similar view of the other shaft or spindle.

Fig. 6 is a detail sectional view illustrating the manner of mounting the eccentrically arranged pins.

Fig. 7 is a detail perspective view of one of the clothes pins.

Fig. 8 is an end view of the same.

Like numerals of reference designate corresponding parts in the several figures of the drawings.

In the accompanying drawings, in which

is illustrated the preferred embodiment of the invention, the clothes pin making machine comprises in its construction a standard 1 constructed of wood or other suitable material and provided adjacent to its lower end with an opening 2 adapted to receive a tenon or reduced portion 3 of a base 4 extending from the lower portion of the standard. In practice, the base will be arranged at a slight inclination, being supported at its rear end by the standard and resting at its front end upon the supporting surface, but in the accompanying drawings the standard is shown vertical and the base 70 horizontal for convenience in illustration. The reduced portion or tenon 3 is secured in the opening 2 by a pin 5 piercing the outer portion of the tenon and connected with the standard by a flexible strip 6 to 75 prevent it from becoming lost when the base and the standard are separated for convenience in carrying or storing. The standard is adapted to be arranged flat upon the base when disconnected therefrom, and the 80 clothes pin making machine will occupy only a comparatively small amount of space and may be easily transferred from one point or place to another.

The standard is equipped at its upper end 85 with a pair of spaced parallel upwardly projecting jaws 7 of rectangular form and constructed from oblong plates or blanks which are angularly bent at spaced points to form the said jaws 7, an intermediate 90 supporting portion 8 and depending attaching portions 9. The transverse supporting portion 8 is arranged at right angles to the jaws 7 and the attaching portion 9 and it forms with the said attaching portion 95 an approximately L-shaped shank to fit against the upper end and side face of the standard. The attaching portions are secured to the standard by means of a transverse bolt 10 and screws 11, but any other 100 suitable fastening means may of course be employed for this purpose. The bolt pierces the standard and the attaching portions and the screws are embedded in the standard. The jaws are spaced apart a sufficient distance to permit a piece of wire to be introduced into them and they are rigid and enable the wire to be bent to form transverse loops 12 of a wire clothes pin 13.

The terminal of the wire at one end of 110 the clothes pin is bent or partially coiled to form an eye 14 and at a diagonal point of

the transverse loops to provide an eye 15 or spring coil, by means of a lower shaft or spindle 16, preferably consisting of a tube having a head 17 at one end provided with 5 spaced eccentrically arranged projections or pins 18, which are adapted to engage the wire and form a coil therein when the shaft or spindle 16 is rotated. The head 17 may be conveniently formed by a coupling and 10 the projections 18 may consist of pins embedded in a block 19 fitted in the coupling and abutting against the adjacent end of the shaft or spindle. The wooden block 19 is driven into the coupling and the body 15 portion of the shaft or spindle 16 forms a convenient stop. Any other suitable means may of course be employed for forming the head and mounting the eccentric projections. The coupling is also adapted to fit 20 against the standard at one side thereof and the shaft 16 is pierced at the other side of the standard by a bolt 20 which coöperates with the head 17 to retain the shaft or spindle in the opening 21 of the standard. 25 The spindle or shaft 16 is provided, at the end opposite that in which the head is located, with a crank handle 22 by means of which it is rotated.

In forming the loop or eye 14, the end 30 portion of the wire is inserted between the pins 18, the spindle 16 being then turned through a complete rotation. During the turning of the spindle, the wire is gripped and tensioned in the direction opposite to 35 the direction of rotation of the spindle, the end portion of the wire being thus wrapped about the pins 18 to form loop 14. It is important to note that during the first half rotation of spindle 16, the extreme terminal portion of the wire will be bent about one of the pins only so as to form a relatively small loop, the wire being subsequently bent about both of the pins so as to form the relatively large loop 14, the small 40 loop being cut off of the free end of the larger loop so as to avoid objectionable projections. In forming the smaller loop 15, the wire is inserted between the two pins 18 and spindle 16 is then moved through a 45 half rotation thus bending the wire about one of the pins 18 in the manner previously described so as to produce the relatively small loop or eye 15, the arms of the wire at the opposite terminals of this loop or eye 50 being disposed substantially at right angles to each other so as to permit ready form-

ing of the coils 23, due to the fact that, as stated, spindle 16 is moved through a half rotation only in forming this loop.

The wire of the clothes pin is coiled to 55 form the relatively large coils 23 and the ring 24 by means of an upper shaft or spindle 25 mounted in an opening 26 of the standard and provided at one end with a longitudinal slot 27 adapted to receive the 60 transverse loops 12 which are of a length approximately the diameter of the large coils 23. The shaft or spindle 25 is adapted to be rotated while the transverse loops are in the slot 27 to permit the coils 23 to be 65 formed around the said loops. The clothes pin has a shank 28 which connects the ring 24 with the spring coils 23, and the said ring is adapted to be formed on the slotted portion of the shaft or spindle, after which the 70 terminal 29 of the wire may be twisted or bent around the stem 28 by the eccentrically arranged projections 18. The shaft or spindle 25 is provided at opposite sides of the standard with pins or keys 30 like 80 the pin or key 20 of the shaft or standard, to prevent longitudinal movement of the shaft or spindle 25 in the opening 26. Any other suitable means may of course be employed to limit or prevent such longitudinal 85 movement, and the shaft 26 is provided with a crank handle 31 by means of which it may be rotated.

What is claimed is:

A clothes pin making machine including 90 a standard having a transverse opening, a rotary shaft extending through the said opening and provided at one end with a tubular head of greater diameter than the shaft and projecting from such end of the 95 same and forming an inner exterior shoulder or stop to fit against the said standard, said shaft also forming a shoulder interiorly of the said head, a wooden plug or block driven into the head and fitting 100 against the shoulder formed by the shaft, eccentrically arranged pins embedded in the block within the head and projecting beyond the same for engaging a wire, and means for rotating the shaft. 105

In testimony whereof I affix my signature in presence of two witnesses.

NORMAN M. MIMS.
